[57] CLAIM

The ornamental design for a shaker bath, as shown and described.

DESCRIPTION

FIG. 1 is a front elevational view of a shaker bath, showing my new design;

FIG. 2 is a rear elevational view thereof;

FIG. 3 is a side elevational view thereof;

FIG. 4 is a side elevational view thereof, opposite that shown in FIG. 3;

FIG. 5 is a top plan view thereof, the series of circles being partially shown for ease of illustration; and

FIG. 6 is a bottom plan view thereof, the cross-line pattern on the bottom of the design is partially shown for ease of illustration.

FIG. 1

FIG. 2

FIG. 3

FIG. 4

FIG. 5

FIG. 6
